UNITED STATES PATENT OFFICE.

JAMES F. BAILEY, OF COLUMBIA, SOUTH CAROLINA.

WRENCH.

Application filed April 1, 1922. Serial No. 548,698.

To all whom it may concern:

Be it known that I, JAMES F. BAILEY, a citizen of the United States, residing at Columbia, in the county of Richland and 5 State of South Carolina, have invented certain new and useful Improvements in Wrenches; and I do hereby declare the following to be a full, clear, and exact description of the invention, such as will enable 10 others skilled in the art to which it appertains to make and use the same.

This invention relates to a tool of the wrench type embodying a handle and inner and outer jaws, the inner jaw being slidable 15 along the handle and held in the required adjusted position.

The primary object of the invention is the provision of a wrench of the type aforesaid embodying an improved form of handle and 20 jaw structure and arrangement, whereby the tool may be cheaply manufactured and assembled and is capable of being effectively used, either as a nut or pipe wrench, and which may have both jaws fixed but relatively 25 adjustable, or which may have one of the jaws relatively fixed and the other pivoted, according to the specific formation of the tool.

Other objects and advantages will be apparent and suggest themselves as the nature 30 of the invention is understood.

While the drawings illustrate an embodiment of the invention it is to be understood that in adapting the same to meet different 35 conditions and requirements, various changes in the form, proportion and minor details of construction may be resorted to without departing from the nature of the invention.

Referring to the accompanying drawings 40 forming a part of the application,

Figure 1 is a side view of a wrench embodying the invention,

Figure 2 is a view similar to Figure 1, the handle section on the near side being removed,

Figure 3 is a rear edge view of the wrench,

Figure 4 is a transverse section on the line 4—4 of Figure 1, looking in the direction of the arrows,

Figure 5 is a detail view of the outer jaw section separated to show more clearly the tongue and groove joint between,

Figure 6 is a side view of a modification,

Figure 7 is a rear edge view thereof,

Figure 8 is a detail view of the outer end

portion of the handle with the near section removed and the outer jaw in section,

Figure 9 is a detail view of the inner jaw and a portion of the shank to which the jaw is pivoted,

Figure 10 is a detail longitudinal section on the line 10—10 of Figure 6,

Figure 11 is a detail section on the line 11—11 of Figure 6, and

Figure 12 is a detail view of the facing or grip for the inner pivoted jaw.

Corresponding and like parts are referred to in the following description and designated in the several views of the drawings by like reference characters.

The wrench comprises a handle and an outer and an inner jaw, the latter being slidable along the length of the handle. The handle is of sectional formation, the sections being of similar or like formation and each section comprising a bar 1 and a semi-cylindrical portion 2, the latter having an inner rib 3 at its outer end which constitutes an element of the swivel connection between the handle and the adjusting nut by means of which the inner jaw is moved. When the sections of the handle are assembled, the bar portions 1 are spaced apart and extend in parallel relation, whereas the semi-cylindrical portions 2 come together and are secured in any manner, either by fastenings 4 or by being welded. The fastenings 4 may consist of rivets, bolts or machine screws. The outer jaw 5 is fixed and comprises similar sections which are formed with the respective sections of the handle. A tongue and groove joint is formed between the sections comprising the jaw 5 to insure the strain on the jaw when the tool is in operation being uniformly sustained by both sections. The tongue is designated by the numeral 6 and the groove by the numeral 7 and these elements match when the sections of the jaw are assembled. Fastenings 8, such as rivets, machine screws or bolts, connect the sections of the jaw when the parts are placed together.

The inner jaw 9 is slidable lengthwise of the handle towards and away from the outer fixed jaw. The jaw 9 has a shank 10 which is slidable between the bars 1 and into the cylindrical portion of the handle. A threaded stem 11, forming a part of the shank 10, cooperates with a nut 12 which is disposed within the cylindrical portion of the handle and has a swivel connection

therewith, an annular groove 13 formed in the outer side thereof receiving the rib 3. A fingerpiece 14, forming a part of the nut 12, abuts the outer end of the handle and 5 conforms thereto and is roughened or milled upon its outer side to enable the hand to obtain a firm grip thereon when rotating the nut 12 to adjust the jaw 9. The inner or head portion of the jaw 9 receives the bar 10 portions 1 of the handle, whereby the jaw is braced so as to withstand the strain to which it is subjected when the tool is in operation. The jaws 5 and 9 are relatively fixed, that is, they have no pivotal movement, the outer jaw 5 being immovable and the inner jaw 9 adjustable.

In the modification shown in Figure 6 and the detail views thereof, the general construction and arrangement of the tool 20 corresponds with that herein before described, corresponding parts being designated by like reference characters. The main difference resides in the inner jaw and its mounting, the same being pivoted and 25 both jaws being disposed at a right angle to the length of the handle, whereas the corresponding jaws in the form shown in Figure 1 are inclined to the handle.

The inner pivoted jaw 15 of the modification is formed with a tongue 16 which is pivoted to the shank 10^a, the forward end of which is cut away to receive the tongue 16. A pivot 17 passes through the overlapping parts and pivotally connects them. 35 A spring 18 is interposed between the forward portion of the jaw 15 and the handle 1 and serves to hold the gripping jaw 15 pressed outwardly to grip a pipe or like article and enable said jaw to ratchet when 40 oscillating the wrench to turn the pipe or other work gripped between the two jaws. The recesses 19 formed in the sides of the jaw 15 are forwardly widened to admit of the jaw having a limited pivotal movement 45 which is essential to admit of its ratcheting when the tool is in operation. Each of the jaws has a facing or grip section 20 detachably fitted thereto and formed of high grade steel to maintain the biting edges of the 50 teeth formed thereon. The facing or grip sections 20 may be attached to the jaws in any preferred way whereby they may be removed when required.

What is claimed is:

55 1. A wrench comprising a handle having a jaw at its outer end and comprising similar sections, each including a bar and a semi-cylindrical portion, an inner jaw slid-

able between the bars of the handle, and means located within the cylindrical portion 60 of the handle for adjusting the inner jaw towards and away from the outer jaw.

2. A wrench comprising a handle consisting of similar sections, each including a bar and a semi-cylindrical portion, a fixed jaw 65 at the outer end of the handle comprising complementary sections formed with the respective bars of the handle, an inner jaw slidable between the bars comprising the handle, and means within the cylindrical portion of the handle for adjusting the inner jaw towards and away from the outer jaw.

3. A wrench comprising a handle embodying similar sections, each section including 75 a bar, a semi-cylindrical portion and a jaw portion, the jaw and semi-cylindrical portions of the bars coming together and the remainder being spaced apart, a shank between the handle sections, a jaw pivotally 80 mounted upon the outer end of the shank, a spring carried by and normally exerting a pressure upon the pivotal jaw to hold it at the limit of its forward pivotal movement.

4. A wrench comprising a handle including laterally spaced and separable sections and having a jaw at its outer end, a shank arranged between the spaced portions of the handle, a jaw pivoted to the shank and having recesses in opposite sides to receive 90 the spaced portions of the handle, said recesses being widened forwardly to admit of the jaw having a limited pivotal movement, and a spring between the pivoted jaw and shank to normally hold the jaw at the limit 95 of its pivotal movement.

5. A wrench comprising a handle consisting of similar sections, each section including a bar, a jaw portion and a semi-cylindrical portion, the jaw portions of the bars coming together and having a tongue and groove joint between them, a shank between the bars, a jaw pivotally mounted upon the forward end of the shank, a spring carried by and normally holding the jaw at the limit 100 of its forward pivotal movement, and means within the cylindrical portion of the handle for adjusting the shank and holding the same in the required adjusted position.

In testimony whereof I affix my signature 110 in presence of two witnesses.

JAMES F. BAILEY.
